GOLF CLUB COVER

Monroe H. Rosenow, Brookfield, Wis., assignor to ABC Industries, Inc., Milwaukee, Wis., a corporation of Wisconsin

Filed May 24, 1963, Ser. No. 75,046

Term of patent 14 years

(Cl. D34—5)

Fig. 1.

Fig. 2.

The dominant features of my design reside in those portions thereof shown in full lines.

The design is characterized by the fact that the side wall which is secured at its edges to the top and bottom panels, has a substantially uniform width throughout its length.

I claim:

The ornamental design for a golf club cover, as shown and described.
